US00D727558S

(12) **United States Design Patent**
Tang et al.

(10) **Patent No.:** **US D727,558 S**
(45) Date of Patent: **** Apr. 21, 2015**

(54) **OPTICAL LENS**

(71) Applicants: **Ledlink Optics, Inc.**, New Taipei (TW);
Ledlink Optics (Dong Guan) Co., Ltd.,
Guangdong (CN); **Yang Zhou Ledlink**
Optics Co., Ltd., Jiangsu Province (CN)

(72) Inventors: **Te-Lung Tang**, New Taipei (TW);
Chih-Ming Wei, New Taipei (TW)

(73) Assignees: **Yang Zhou Ledlink Optics Co., Ltd.**,
Jiangsu Province (CN); **Ledlink Optics**
(Dong Guan) Co., Ltd., Guangdong
(CN); **Ledlink Optics, Inc.**, New Taipei
(TW)

(**) Term: **14 Years**

(21) Appl. No.: **29/441,980**

(22) Filed: **Jan. 11, 2013**

(51) LOC (10) Cl. **26-99**

(52) U.S. Cl.

USPC **D26/120**

(57) **CLAIM**

The ornamental design for an “optical lens,” as shown and described.

DESCRIPTION

FIG. 1 is a perspective view of a “optical lens” showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a sectional view taken along line 8-8 of FIG. 6.

1 Claim, 5 Drawing Sheets
